[57] CLAIM

The ornamental design for a chair, as shown and described.

DESCRIPTION

FIG. 1 is a front perspective view of a high back chair embodying my invention.

FIG. 2 is a front elevational view;

FIG. 3 is a rear elevational view; and

FIG. 4 is an elevational view showing the left side thereof.

The right side of the chair not shown is a mirror image of the side shown in FIG. 4.

FIG. 1.

FIG. 3.

FIG. 2.

FIG. 4.
